UNITED STATES PATENT OFFICE

JAMES H. TAYLOR, OF NEW YORK, N. Y., ASSIGNOR TO THE AMERICAN LAUNDRY MACHINERY COMPANY, OF CINCINNATI, OHIO, A CORPORATION OF OHIO

GARMENT PRESS

Application filed May 12, 1924. Serial No. 712,585.

This invention relates to improvements in power operated garment presses.

Garment presses have been provided wherein power means closes the press, produces and maintains an ironing pressure for the pressing operation, and then opens the press. To prevent possible injury to the operator of the press, such as the crushing or burning of his hands, safety devices such as finger guards have been provided. In some instances, these guards prevent the application of the ironing pressure until the guard has moved to its lowermost guarding position. In other instances, interruption of the downward movement of the guard actuates a switch to stop the motor and hence the closing of the press by power means. These three cycle power presses are also often provided with manually operable emergency means for partially opening the press to avoid further injury to the operator or damage to the work.

The object of the present invention is to provide an improved pressing machine of the type wherein power means performs the triple function of closing the press, producing and maintaining ironing pressure for the pressing operation, and then opening the press. Improved safety means are provided for effectively preventing injury to the operator, said means including a safety finger guard adapted to travel with but in advance of the movable pressing member, when the latter is moving to pressing position, said guard being adapted, when its downward guarding movement is interrupted, to effect the breaking of an emergency toggle and thereby not only arrest the closing movement of the press but to also effect a partial opening movement thereof.

A further feature of the present machine is the provision of automatic power operated means for breaking the emergency toggle and thereby effecting opening movement of the press when the object or material on the bed exceeds a predetermined thickness. This feature is particularly important in pressing work of a more or less uniform thickness, for if the arrangement or lay of the work is improper, so that the work exceeds the predetermined maximum thickness, the movable

pressing members will be automatically and instantly raised before the work is improperly pressed. Moreover, if for any reason the safety finger guard fails to work properly and the hand of the operator is resting on the bed when the upper pressing member comes into engagement therewith, the emergency toggle will be automatically broken and the movable pressing member thereby raised and injury to the operator prevented. As a further safeguard, the machine is provided with simple and conveniently arranged means for manually breaking the emergency toggle to thereby arrest the closing movement of the press and effect opening movement thereof.

Further objects of the invention are in part obvious and in part will appear more in detail hereinafter.

In the drawings, Fig. 1 is a side elevation of a garment press embodying my invention; Fig. 2 is a fragmentary plan view of the safety finger guard mechanism; Fig. 3 is a detail sectional view of the motor timing mechanism; Fig. 4 is a detail view of the motor switch mechanism; Fig. 5 is a wiring diagram illustrating the control of the motor; Fig. 6 is a side elevation of the press, showing more in detail the safety finger guard mechanism, the upper portions of said view being taken in the plane of line *a*, Fig. 2, while the lower portion is in the plane of line *b*, Fig. 12; Fig. 7 is a vertical sectional view of the lower portion of the machine, illustrating the position of the parts when the press is closed; Fig. 8 is a detail sectional view taken in the plane of the line *c*, Fig. 12; Fig. 9 is a detail sectional view of the lower portion of the machine, showing the arrangement of the parts when the head has engaged an obstruction on the bed, two positions being shown, the first showing the pawl operating mechanism in engagement and the second showing the emergency toggle broken; Fig. 10 is a similar view showing the position of the parts with the head raised, other positions of the parts being shown in dotted lines, one with the head engaging the buck and the other when ironing pressure is first being applied; Fig. 11 is a detail view of the magnetic brake; Fig.

12 is a horizontal sectional view taken on the line 12—12, Fig. 7; Fig. 13 is a horizontal sectional view taken in the plane of the line *d*, Fig. 7; and Fig. 14 is a similar view taken in the plane of the line *e*, Fig. 7.

Referring to the drawings, the pressing machine therein illustrated comprises a main frame 1 upon the pedestal 2 of which is mounted the padded bed or lower pressing member 3. The frame is provided with a rearwardly and upwardly extending arm 4 in the upper end of which is pivotally mounted at 5 the pressure bar 6 which carries at its forward end the padded and heated head 15 or upper pressing member 7.

The operating mechanism for moving the head into and out pressing engagement with the bed is of the toggle type. Said mechanism includes an upper main toggle member 10, the upper end portion of which has sliding engagement in a swivel block 11 suitably mounted in the rear end portion of pressure bar 6. An abutment cap 12 is secured upon the upper end of said toggle member 25 while below the swivel block, said member is provided with an adjustable collar 13 which forms the lower abutment for a spring 14, the upper abutment for which is the swivel block 11.

30 The lower end of said toggle member is connected at 15 to the upper end of the lower main toggle member 16, which in turn has its lower end connected at 17 to the upper end of an emergency toggle link 18. The 35 lower end of this emergency toggle link is loosely mounted on a pin 19 secured in the ears 20 of the machine base.

The main toggle formed by members 10 and 16 is straightened and broken to there- 40 by respectively close and open the press by power means, in the present embodiment, by a motor 25 mounted upon a bracket 26 suitably secured to the machine frame. Coupled to the driving shaft of this motor is a worm 45 shaft 27 carrying a worm 28 which meshes with a worm wheel 29 fast upon the main operating shaft 30. The main toggle is connected to this operating shaft by mechanism which comprises a tubular member 31 con- 50 nected to the toggle knuckle 15 and having slidably mounted therein a plunger 32, the outer end of which is connected to a crank arm 33 fast upon the main operating shaft.

As clearly shown in Fig. 7, a collar 34 55 is pinned on the inner end portion of the plunger, the securing pin 35 projecting from said collar engaging in an elongated slot 36 in the tubular member 31. Between said collar and the inner end of the tubular mem- 60 ber is a spring 37, while between said collar and a lock nut 38 at the outer end of the tubular member is a cylindrical cushioning sleeve 39, of rubber or other suitable material. It will thus be seen that the plunger has but 65 limited movement in the tubular member and

that yielding cushioning means are provided for both directions of its movement.

The switch mechanism for the motor comprises a casing 40 carried by the motor bracket 26. Suitably arranged within said casing 70 are upper and lower pairs of contacts 41 and 42, respectively, with which respectively co-operate the upper and lower movable bridging contacts 43 and 44 which are carried by a vertically disposed rod 45. The upper end 75 of this contact carrying rod is connected to a rod 46, which in turn is connected to the lower arm of a bell-crank lever 47 loosely mounted on the frame stud 48. Connected to the upper arm of said lever is a horizontally 80 disposed rod 49 slidably mounted in the depending bracket 50 of a work table 51 secured about the lower end portion of the frame pedestal 2. A knob 52 is mounted on the front end of rod 49, which knob is grasped by the operator in actuating the motor switch. The contact carrying rod 45 is held by a spring 53 in either its lower or upper position to thereby respectively effect engagement of upper contacts 41, 43 or lower contacts 42, 44. One end of this spring is secured to the upper arm of the bell-crank lever 47 while its other end is secured to a de- 85 pending arm 54 fast upon the lever pivot stud 48. Horizontal movement of the knob carrying rod 49 throws the spring 53 on one or the other side of pivot stud 48 and thereby holds the switch rod 45 in either its upper or lower position, depending upon the direction in which rod 49 is moved.

100 Suitable timing mechanism for the motor is also provided for controlling the cycles of operation, including the closing and opening cycles of the press. The mechanism here shown comprises a casing 60 within which is 105 an insulating block 61 fast upon one end of the main operating shaft 30. Fast upon said insulating block is a metal distributing ring 62 engaged at all times by a current receiving contact shoe 63. Mounted upon the distributing ring is a second contact shoe 64 which is adapted to engage the substantially semi-circular contact segments 65 and 66 ad- 110 justably secured to the inner surface of cas- ing 60, which segments may be respectively 115 termed the "opening" and "closing" seg- ments.

The coupling for the motor driving shaft and the worm shaft 27 includes a brake drum 70 with which cooperates a brake band 71 which is in braking engagement with the drum when the current from the motor is off. One end of said brake band is connected to a bracket 72 on which is mounted a coil 73, while the other end of said brake band is 120 connected to a stem 74. Said stem extends through said bracket and has a spring 75 interposed between the bracket and the stem head, the effect of said spring being to normally hold the brake band in engagement 125 130.

with the brake drum. An armature 76 is pivotally mounted to the bracket 72 and carries at its free end a screw 77 adapted, when the coil is energized, to engage the head of the stem 74 and move the brake band from engagement with the brake drum.

The operation of the parts thus far described is as follows, reference being had to the wiring diagram in Fig. 5, in which the press is open.

80 and 81 represent the main current lead lines and 82 an ordinary snap or other switch which forms no essential part of the present invention. Leading from this switch, the positive line 80 is connected to the stationary contact shoe 63, through which current is supplied to the distributor ring 62, thence to movable contact shoe 64 and to the "closing" contact segment 66. Leading from this segment is a line 83 connected to one of the lower motor switch contacts 42, which is now out of engagement with its cooperating bridging contact 44. The negative line 81 leads to the motor 25, from which extends a line 84 which leads through the brake coil 73 to the other lower contact 42 of the main line switch. Leading from this contact is a line 85 connected to one of the upper switch contacts 41 which is now in engagement with its cooperating bridging contact 43. Connected to the other switch contact 41 is a line 86 leading to the "opening" contact segment 65. When the parts are in the position shown in the wiring diagram, the press is open and the motor is running idle due to the fact that the movable contact shoe 64 is in engagement with "closing" contact segment 66 which is connected to one of the lower switch contacts 42 which is, at this particular time, out of engagement with its cooperating contact 44.

When the operator wishes to close the press, he pulls the knob carrying rod 49 outwardly, which brings into engagement the lower switch contacts 42, 44, completes the circuit to the "closing" contact segment 66 and starts the motor. The timing mechanism is so constructed and adjusted that the head engages the bed at the time the contact shoe 64 leaves the "closing" segment 66 and engages the "opening" segment 65. This latter segment is connected to one of the upper switch contacts 41 which are now out of engagement with their cooperating bridging contact 43. The press, therefore, comes to a state of rest with the pressing members in engagement. The reverse or opening cycle is obvious, it being only necessary to push in the knob carrying rod 49 to bring switch contacts 41, 43 into engagement and thus complete the circuit to the "opening" contact 65.

In order to prevent injury to the machine operator, such as the crushing and burning of his hands or arms a safety finger guard 95 is provided. Said guard travels in advance of the head when the latter is moving

to pressing engagement with the bed, and is so constructed that interruption of its descent breaks the emergency toggle formed by members 16 and 18 and not only prevents the head from coming into engagement with the bed but also partially raises the head. Injury to the operator's hands and arms is, therefore, effectively prevented.

In the specific embodiment here illustrated, said guard so closely surrounds the head, to which it conforms in shape, that the operator cannot get his fingers therebetween. The guard is mounted upon the front end of a pair of arms 96 which have sliding engagement in a pair of swivel blocks 97 mounted on the trunnions 98 of the lever bar pivot 5, the rear end of each of said arms being provided with a counter-weight 99. Preferably, the head or upper pressing member is provided with yielding pads 100 which are engaged by the guard arms when the guard is in its lowermost position. Downward movement of the guard is limited by the engagement with the frame arm 4 of a screw 101 adjustably secured in a bracket 102. This bracket is secured to a spacer strip 103 to which the guard is secured, said strip being carried by brackets 104 secured to the guard arms.

The mechanism by means of which interruption of the guard descent breaks the emergency toggle is as follows:

Pivotedly connected to a lug at one end of the spacer strip is a link 110 to the upper end of which is pivotally connected a stem 111. The free and headed end portion of this stem passes through an opening in the upper arm of a bellcrank lever 112, a spring 113 being interposed between said lever and a fixed collar 114 on the stem. This bellcrank lever is pivoted at 115 in the upper end of a bracket 116, the lower end of which is clamped to the hub of the pressure bar pivot member 6. The other or lower arm of the bellcrank lever 112 is provided with a tooth or projection 117, adapted for cooperation with the teeth 118 of the upper arm or quadrant of a lever 119 pivoted intermediate its ends on the hub of the pressure bar pivot member 6. The lower end of this lever 119 is bifurcated to receive a swivel block 120 through which extends the upper end portion of a rod 121. Said rod is provided above and below said block with fixed collars 122 and 123, a spring 124 being interposed between the block and the upper collar 122.

The lower end of rod 121 is connected to a lever 125 fast upon a shaft 126 journaled in the machine frame. Fast upon said shaft is a cam 127 which is adapted, when the shaft is given rotary movement, to engage a pawl 130 and move it upwardly into engagement with the teeth 131 of a disk 132 secured to and rotating with the crank arm 33. A stop 125^a adapted to engage the shoulders 126^b of the

- lever 125 limits the movement of this lever, as clearly indicated in Fig. 8. Said pawl is pivotally mounted at 130^a, intermediate its ends, upon the upper end of a lever 134, which 5 in turn is pivotally mounted intermediate its ends on the frame stud 135. Pivotally connected to the lower end of lever 134 is a link 136, the lower end of which is connected to the knuckle pin 137 of the links 138 and 139. 10 The other end of link 138 is pivotally mounted on a pin 140 carried by the machine base while the other end of link 139 is connected to the knuckle pin 17 of toggle members 16 and 18 which constitute the emergency toggle. 15 The emergency toggle formed by members 16 and 18 is broken by the guard mechanism in the following manner.
- In the normal position of the parts with the press open, as shown in Fig. 6, the weight of 20 the guard, applied to the pawl 117 through the link rod 111 and its headed end, holds the pawl out of engagement with the ratchet teeth 118. When the downward travel of the guard is interrupted, say by said guard striking the operator's hands or arms, the tooth 117 of the bell-crank lever 112 is moved to engage the teeth 118 of lever 119, and turns said lever 119 about its pivot in a clockwise direction, Fig. 1, so as to impart rotary movement to the cam shaft 126. Cam 127 thereupon moves the pawl 130 into engagement with the teeth 131 of disk 132 and the clockwise movement of this disk moves the pawl rearwardly, turns lever 134 about its pivot and 30 through links 136 and 139 breaks the emergency toggle. The head is, therefore, prevented from coming into engagement with the bed and injury to the operator is prevented. 35
- The means for straightening the emergency toggle after it has been broken comprises a finger 145 adjustably secured to the web 146 of the lower main toggle member 16. Let us assume that the press has completed 40 the closing cycle and that the emergency toggle is broken. By pushing in the knob carrying rod 49, the motor is started. Crank arm 33 in completing the opening cycle pulls forward the upper end of the lower main toggle member 16, causing finger 145 to engage link 139. Said finger now acts as a fulcrum and the portion of toggle member 16 above said finger forces the emergency toggle to straightened position. 45
- In order to prevent the pressing of work improperly arranged on the bed, suitable means is provided for breaking the emergency toggle when the work on the bed exceeds a predetermined maximum thickness. Said 50 means comprises a collar 150 fast on the inner end portion of plunger 32 and provided with a pair of depending ears 151 in which a pin 152 is non-rotatably mounted. A lever 153 has one of its ends pivotally mounted on said pin and its other end connected by pin 55 154 to a pair of links 155. The upper ends of these links 155 are pivotally mounted upon the studs 156 of the collar 157, which is adjustable on the tubular casing 31 by the screw 158, said collar being secured in any adjusted position by the set screw 159. Lever 153, is provided at its rear end with a depending toe 160 adapted, when an obstruction is engaged on the bed, such as work improperly arranged, to engage a plate 161 adjustably secured to the rear end of pawl 130. Said pawl will thus be moved by said depending toe into engagement with the disk teeth 131 and the emergency toggle broken, as before described. The only pressure exerted upon the work or other object on the bed is that which is sufficient to compress spring 37 in tubular member 31, which is light and insufficient to damage the work or injure the operator's hands. By adjusting the distance 60 between the pivot points 152 and 156, the mechanism can be set so as to cause the breaking of the emergency toggle by any desired thickness of material on the bed. This feature is particularly useful when pressing garments of a more or less uniform thickness, so that if the arrangement or lay of the work is disturbed, causing bundling of the work, the emergency toggle will be broken before the work is improperly pressed. An additional safety feature is also provided by the mechanism just now described, for if the safety guard fails to function and the operator's hands are resting upon the bed or the work, his hands will cause the lever toe 160 to engage the pawl plate member 161 and effect the breaking of the emergency toggle and the immediate raising of the upper pressing member so that his hands may be withdrawn and injury thereto avoided. 65
- Means is also provided for manually breaking the emergency toggle, said means in the embodiment here shown comprising a cam 165 adapted to engage a roller 166 loosely mounted upon one end of the pawl pivot pin 130^a of the lever 134. Connected to said cam is a link 167 to which is connected the lower end of a vertically disposed rod 168, the upper end of which is connected to one arm of a bell crank lever 169 pivoted on the frame stud 170. Connected to the other arm of said bell-crank lever is a horizontally disposed rod 171 slidably mounted in the bracket 172 depending from the work table 61. This rod 171 carries at its forward end a knob 173 between which and the bracket 172 a spring 174 is interposed, the tendency of said spring being to normally keep the vertically disposed rod 168 in raised position and the cam 165 out of interfering relation with the pawl roller 166. By pushing in the knob carrying rod 171 the cam 165 is brought into engagement with lever roller 166, and the upper end of lever 134 moved rearwardly by said cam, the movement of lever 134 effecting the breaking 70 75 80 85 90 95 100 105 110 115 120 125 130

of the emergency toggle in the manner before described. When the head is in raised position, the breaking of the emergency toggle is prevented by the finger 145 of the lower 5 main toggle member 16.

It will thus be seen that I have provided a power operated pressing machine in which the closing movement of the press may be arrested and opening movement effected by 10 three separate and distinct means, two of which are automatic and power controlled. First there is the safety finger guard means; second, the means sensitive to the thickness of the object or work on the bed; and third, 15 manual means for operation by the operator. While the machine is capable of extremely great production, the operator is amply protected against injury.

What I claim is:

20 1. A pressing machine, comprising relatively movable pressing members, main toggle members for producing pressure between them, power means, actuating mechanism operatively connecting the power means to said 25 toggle members, an emergency member connected to said main toggle members and movable into operative and safety inoperative positions, and power operated means for actuating said emergency member including 30 a controlling part operatively associated with a part actuated by said power means.

25 2. A pressing machine of the kind defined in claim 1 including control means for said 35 emergency member actuating means responsive to the thickness of an article between the pressing members.

30 3. A pressing machine of the kind defined in claim 1, including control means for said 40 emergency member actuating means, said control means comprising a manually operable member on the machine frame.

35 4. A pressing machine of the kind defined in claim 1, including safety guard means 45 located at the entrance to the pressing space and connected to said emergency member actuating means for controlling the same.

40 5. A garment press, comprising relatively 50 movable pressing members, toggle members for actuating the same, a power source, and connections therefrom to the toggle members for operating the same, an emergency pressure releasing member cooperating with said toggle members, and means for actuating said pressure releasing member, including 55 a part in the connections from said power source to the toggle members.

60 6. A garment press of the kind defined in claim 5, including controlling means for 65 said actuating means responsive to the thickness of an article between the pressing members.

65 7. A pressing machine of the kind defined in claim 5 provided with controlling means for said actuating means including guard

means located at the entrance to the pressing space.

8. A pressing machine of the kind defined in claim 5, provided with controlling means for said actuating means including a manually operable member on the machine frame.

In testimony whereof I hereby affix my signature.

JAMES H. TAYLOR.
